William Townsend 1754X
Letters Patent

The Schedule referred to in these Letters Patent and making part of the same containing a description in the words of the said William Townsend himself of his Invention.

The advantages arising from this improvement over other machines for similar purposes, are that, a great power is obtained at a small expense: as the machine is very simple in its construction and requires but little room. The power is obtained by the application of two levers connected with a roller or cylinder, one end of the first lever enters a mortise in a vertical piece called a holder, the lower end of which is secured to the frame, by a pin passing through the two side pieces of the frame and the holder, and serves as a centre for the holder to revolve or turn upon. There is also a pin in the upper part of the said mortise, and a semicircle cut on the upper edge of the lever, which receives said pin, near the holder, is a vertical slider, the upper end of which has a long chase mortise through which the lever passes, the slider is perforated at proper distances, the whole length of the mortise aforesaid, the lower end of this slider bears upon the substance to be compressed, and a pin put through one of the said holes, the most suitable height forms a fulcrum for the lever, to the other end or longest brachia of the lever is attached a chain, rope, or other flyable substance, which is fastened to and winds round the said roller cylinder before the sides of the frame. One end of this roller projects beyond the side of the frame, the projecting end is perforated with several holes in different directions, passing through its centre, which holes receive a second lever which serves to turn the second roller or cylinder and operates as a windlass upon the rope or chain aforesaid. The longest brachia of this

1754X

lever is generally covered to the other, in which case it requires less room to work the machine, but it may be continued in the same line, to any length, at pleasure. at the lower end of this holder is, moveable upon a centre and the motion of the lever in the holder and upon the pistonum, is on round pins, very little friction is produced, a pin or cleat is fixed to the upright sides of the frame under which the cheese board slides, when the cheese is to be turned, the board may be drawn forward sufficiently to turn the cheese upon the board, and these pins or cleats, serve to keep it in a horizontal position.

Witnesses.
